UNITED STATES PATENT OFFICE

EDWARD G. PARVIN, OF ROSELLE, NEW JERSEY

RADIO CIRCUIT

Application filed August 4, 1931. Serial No. 554,965.

This invention relates in general to improvements in radio circuits, particularly those of the type using multi-electrode audion.

5 The general object of this invention is the provision of novel forms of radio circuits having a high degree of sensitivity and selectivity.

10 Another object of this invention involves radio circuits employing four electrode audions.

These and many other objects as will appear from the following disclosure are secured by means of this invention.

15 This invention resides substantially in the construction, combination, arrangement and relative location of parts all as will be more fully pointed out hereinafter.

20 Referring to the drawing in which the same reference numerals will be used throughout the several views to indicate the same or similar parts,—

25 Figure 1 shows the basic connection of a four electrode tube as employed in this invention;

Figs. 2 and 3 show two forms of circuits employing this basic connection;

30 Fig. 4 is a modified form of circuit employing this invention showing an audio amplifier comprising two vacuum tubes in parallel;

Fig. 5 is a modified form of connection employing a five electrode tube.

35 As shown in Figure 1, the invention employs a four electrode audio comprising the usual evacuated vessel 1 having an indirectly heated cathode 3 which may be heated by means of the heater 2.

40 At 3, is the usual control grid and at 4 are anodes which may be made in the form of continuous plates or perforated plates in the many well known forms. The input circuit is connected between the cathode and the outer cold anode 6. The output circuit is connected between the grid and a potentiometer 8 connected across the battery 7 which is interposed between the cathode and the inner anode 5. Actual experience with circuits employing this fundamental connection have demonstrated that it is a circuit of considerable sensitivity and one which does not need

any radio frequency stages preceding it although they may be used if desired.

This circuit has been shown in more detail in Fig. 2 in which the antenna is indicated at 9 and connected through a suitable condenser 10 through one terminal of a suitable inductance 11 which is grounded. This tuning inductance is bridged by a variable tuning condenser 12. One terminal of the inductance condenser unit is connected to the outer anode 5 and the other terminal is connected to the cathode 3. The inner anode 5 is connected to the cathode to a suitable battery 7 which is bridged by a potentiometer which is connected to one terminal of the primary of the audio frequency transformer 13. The other terminal of this primary is connected to the grid 4. The arrangement in Fig. 3 is somewhat similar to that of Fig. 2 with the exception that in addition to the antenna inductance 11 and its tuning capacity 12, a second inductance 14 bridged by a variable condenser 15 is supplied for tuning the input circuit of the audion.

The second tuned inductance provides a 75 circuit of greater selectivity than that shown in Fig. 2.

The circuit of Fig. 4 is somewhat similar to that of Fig. 3 but includes further details. In this form of circuit the anode 6 and the 80 grid 4 are interconnected by means of a variable resistance 17 by means of which volume control may be effected. The anode 5 is connected as before to the positive side of a suitable current source but in this case the high 85 resistance 16 is connected in series therewith and is bridged by means of a fixed condenser 17. The resistance of the resistor 16 may be of the order of 50,000 ohms and the capacity of the condenser 17 may be of the order of one 90 microfarad. The cathode in this case is connected to the input circuit through resistance 18 which may be of the order of 1,000 ohms. The positive lead to the anode 5 is also connected to the negative lead of the B. supply 95 through the resistances 19 and 20 in series. Resistance 19 may be of the order of 200,000 ohms and resistance 20 may be of the order of 50,000 ohms. Resistance 20 is used as a 100 potentiometer from which a variable lead ex-

tends to the primary of the transformer 13. The secondary of this transformer is connected to the input of two similar audions 21 and 22 connected in parallel. The outer 5 anodes 6 are connected together and to the secondary of the transformer. The grids 4 are connected together and to the input of the transformer 27. The two inner anodes 5 are connected together and are also connected 10 to the input of transformer 27. The output of transformer 27 is connected to a three electrode audion 23 of the usual construction and in the usual manner.

The heaters 2 of the audion are connected 15 through variable resistance 29 to the output leads 28 of a suitable transformer 27. A connection including a variable resistance 30 is connected from the midpoint of the secondary of transformer 27 to the cathode circuit.

20 This circuit has been found to be highly sensitive and very selective and eliminates the necessity of employing radio frequency amplifying stages. The modified arrangement of Fig. 5 employs three anodes in which 25 the input circuit is connected between anode 40 and the cathode. Anode 41, is connected to the cathode through the battery 44. Anode 42 is connected to this battery through the variable tap 43. The output circuit is 30 connected between the grid 45 and the potentiometer 46 connected between the cathode and the variable lead 43.

From the above description it will be apparent that this invention resides in certain 35 principles of construction and operation which may be carried out in other physical forms and I do not therefore desire to be strictly limited to the disclosure as given for the purpose of illustration but rather to the 40 scope of the appended claims.

What I seek to secure by United States Letters Patent is:

1. A radio circuit of the type described 45 comprising in combination a multi-electrode audion including a cathode, a grid and two anodes, an input circuit connected between one anode and the cathode, an output circuit connected between the grid and the cathode and a connection between the other anode 50 and the cathode.

2. A radio circuit of the type described 55 comprising a multi-electrode audion including a cathode and three cold electrodes placed at relatively different distances from the cathode, an input circuit connected between the cold electrode furthest from the cathode and the cathode, an output circuit connected between the cold electrode near the cathode and the cathode and a connection between 60 the other cold electrode and the cathode.

3. A radio circuit of the type described 65 comprising a multi-electrode audion including a cathode and three electrodes placed at relatively different distances from the cathode, an input circuit connected between the

electrode furthest from the cathode and the cathode, an output circuit connected between the electrode near the cathode and the cathode and a connection between the other electrode and the cathode, said connection including a potential source.

4. A radio circuit of the type described comprising a multi-electrode audion having three cold electrodes and a cathode, an input circuit between one cold electrode and the cathode, a connection including a potential source between another of the cold electrodes and the cathode, an output circuit connected between the other cold electrode and the high resistance.

5. A radio circuit of the type described comprising a multi-electrode audion including a cathode and a plurality of cold electrodes, an input circuit connected between one of the cold electrodes and the cathode, an output circuit connected between another of the cold electrodes and the cathode, means for interconnecting the remaining cold electrodes with the cathode, said means including a potential source, two multi-electrode audions each including three cold electrodes and a cathode, an input circuit coupled between one cold electrode of each audion and the cathodes thereof and coupled to the output circuit of said first audion, an output circuit connected between another of the cold electrodes of each of said audions and the cathode and a connection between the third cold electrode of each of said audions and the cathode.

6. A radio circuit as described comprising an audion having a cathode and three cold electrodes, an input circuit connected between one of the cold electrodes and the cathode, a connection between another of the cold electrodes and the cathode including a potential source in series therewith, a resistance shunted across said potential source, an output circuit connected between the third cold electrode and said resistance, and volume control means comprising a variable impedance connected between the cold electrode in the input circuit and the cold electrode in the output circuit.

In testimony whereof I have hereunto set my hand on this 30th day of July A. D., 1931.

EDWARD G. PARVIN.
